(57) CLAIM

The ornamental design for a portion of a display with a user interface, as shown and described.

DESCRIPTION

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever. The following notice applies to the drawing that forms a part of this document: Copyright © 2011 Fanhattan LLC. All rights reserved.

FIG. 1 is a face view of a portion of a display with a user interface, showing our new design; and,

FIG. 2 is a face view of a second embodiment thereof. The broken line showing of the portion of a display and other graphical elements forms no part of the claimed design.
